Attorney, Agent, or Firm—Ostrolenk, Faber, Gerb & Soffen, LLP

[57] CLAIM

The ornamental design for nozzle for tapping containers, as shown and described.

DESCRIPTION

FIG. 1 is a front view of a nozzle for tapping containers showing my new design, the view from all sides being the same;

FIG. 2 is a bottom view thereof;

FIG. 3 is a top view thereof;

FIG. 4 is a top perspective view thereof shown at an enlarged scale; and,

FIG. 5 is a cross sectional view taken along line V—V of FIG. 4.
